UNITED STATES PATENT OFFICE

130,142

DESIGN FOR A PHYSIOTHERAPY STRETCHING TABLE

Bernard H. Stauffer, Los Angeles, Calif.

Application July 15, 1940, Serial No. 93,651

Term of patent 7 years

To all whom it may concern:

Be it known that I, Bernard H. Stauffer, a citizen of the United States of America, residing at Los Angeles, in the county of Los Angeles, State of California, have invented a new, original, and ornamental Design for Physiotherapy Stretching Tables, of which the following is a specification, reference being had to the accompanying drawing, forming a part thereof.

In the drawing:

Figure 1 is a side elevational view of a physiotherapy stretching table showing my new design, and

Figure 2 is an end elevational view thereof.

The opposite side of the table is substantially the same as the side shown in the drawing.

The right end of the physiotherapy stretching table is a closed flat surfaced panel, the opposite end of the table is similar except for an opening to receive the leaf supporting element.

I claim:

The ornamental design for a physiotherapy stretching table, as shown, and described.

BERNARD H. STAUFFER.
